(57) **CLAIM**

The ornamental design for a drinking glass charm mounting assembly, as shown and described.

DESCRIPTION

FIG. 1 is a perspective view of a drinking glass charm mounting assembly showing my new design;

FIG. 2 is an enlarged perspective view thereof;

FIG. 3 is a further enlarged perspective view;

FIG. 4 is a side elevational view thereof;

FIG. 5 is a top plan view thereof;

FIG. 6 is a bottom plan view thereof;

FIG. 7 is a perspective view showing the ornament spaced therefrom;

FIG. 8 is a perspective view of a modified form of my design;

FIG. 9 is a side elevational view thereof;

FIG. 10 is a top plan view thereof; and,

FIG. 11 is a bottom plan view thereof.

The portions shown in broken lines in FIGS. 1, 2 and 7 are for illustration only and form no part of the claimed design.
